[57] **CLAIM**

The ornamental design for a sock hamper, as shown and described.

DESCRIPTION

FIG. 1 is a diagrammatic perspective view of a sock hamper, in the closed position.

FIG. 2 is a diagrammatic perspective view of the sock hamper, in the open position, in full lines with a liner shown inside the hamper in broken lines representing environmental association matter being for illustrative purposes only and forming no part of the claimed design.

FIG. 3 is a front elevational view of the sock hamper.

FIG. 4 is a rear elevational view thereof.

FIG. 5 is a left side elevational view thereof, the right side elevational view being a mirror image of the left side view.

FIG. 6 is a bottom plan view of the sock hamper; and,

FIG. 7 is a top plan view thereof.
